Patented Aug. 10, 1920.

UNITED STATES PATENT OFFICE.

MORRIS LIPPS, OF NEW YORK, N. Y.

HEADREST.

1,349,073.

Specification of Letters Patent. Patented Aug. 10, 1920.

Application filed January 31, 1918. Serial No. 214,653.

To all whom it may concern:

Be it known that I, MORRIS LIPPS, a citizen of the United States, residing at New York, in the county of New York and State 5 of New York, have invented certain new and useful Improvements in Headrests, of which the following its a specification.

This invention relates to adjustable head rests for cots, beds, couches, etc.

10 One of the objects of the invention is to provide such a head rest which is simple and cheap to manufacture and which when adjusted will yield readily with the spring above which it is positioned as the weight 15 of a person is placed upon the spring, without danger of the adjustment being lost.

Other objects and aims of the invention, more or less broad than those stated above, together with the advantages inherent, will 20 be in part obvious and in part specifically referred to in the course of the following description of the elements, combinations, arrangements of parts, and applications of principles constituting the invention; and 25 the scope of protection contemplated will appear from the claims.

In the accompanying drawings, which are to be taken as part of this specification, and in which I have shown a merely preferred 30 form of embodiment of the invention, Figure 1 is a perspective view of a form of cot including my invention; Fig. 2 is a plan view of part of a cot or bed frame including a modified form of the invention; Fig. 3 is a 35 sectional view partly in elevation taken on the line 3—3 of Fig. 2 looking in the direction of the arrows; and Fig. 4 is a view similar to Fig 3 showing how the head rest of Fig. 1 is secured to the frame.

40 Referring to the numerals on the drawings, there is shown at 4 the frame of a cot bed having the usual spring 5 extending between angle iron 6 at the ends thereof. About midway of the length of the angle 45 iron 6 at the head of the frame is a preferably flat bar 7, which has one end secured to the angle iron as by means of a rivet 8, while the bar extends longitudinally of the frame bove the spring, the free end of the 50 bar 7 being depressible. And the upper surface of the free end of the bar 7 carries one or more stop lugs 9, the purpose of which will be hereinafter described. On either 55 side of the bar 7 the angle iron 6 at the head of the frame is provided with apertures 10 in which are accommodated the hooked ends

of a crank shaft 11 so that this crank shaft may move about the angle iron as a pivot, toward and from the bar 7. Pivoted on the transverse portion of the crank shaft is a 60 head-rest frame made up preferably of flat end bars 12 riveted to side bars 14 and an intermediate bar 15 parallel to the end bars 12 and riveted to the side bars 14. The transverse portion of the crank shaft is pivoted between the bars 12 and 15 and bearing straps 16 riveted to the respective bars 12 and 15, so that the head-rest frame may move pivotally about the crank shaft. The lower or forward edge of the frame is de- 65 signed to engage with the stop lugs 9 on the spring bar 7. When not in use the head- 70 rest frame lies flat upon the spring 5, the lower or front edge of the frame occupying its position of most forward extension and 75 the transverse part of the crank shaft lying upon the spring bar 7. It will be observed that the side bars 14 of the frame are of such length that the frame does not at any time contact with the rigid side members of 80 the cot frame, but can only come in contact with the spring bar 7 or with the spring 5. The result of this arrangement is that if the weight of a person is placed, as it is in practice, partly upon the head rest and 85 partly upon the bed spring forward of the head rest, the spring bar 7 is depressed as the bed spring is depressed and the head rest maintains its adjusted position, that is to say, is not apt to be disengaged from the 90 forward edge of the head-rest frame.

A modified form of the device is shown in Fig. 2, in which the ends of the crank shaft are journaled in the side pieces of the cot frame as indicated at 10'. The head-rest 95 frame in this case is connected to the crank shaft as in Fig. 1, but there is no spring bar 7, and instead of the head-rest frame being held in its adjusted position by its engagement with a spring bar 7, the forward edge 100 portion of the head-rest frame is provided with transverse extensions 17 designed to engage with stop lugs 18 on the upper faces of the horizontally disposed portions of the side angle irons of the cot frame. The 105 operation of this form of the device is in general the same as that of Fig. 1.

Inasmuch as many changes could be made in the above construction, and many apparently widely different embodiments of 110 my invention could be made without departing from the scope thereof, it is intended

that all matter contained in the above description or shown in the accompanying drawing shall be interpreted as illustrative and not in a limiting sense.

5 It is also to be understood that the language used in the following claims is intended to cover all the generic and specific features of the invention herein described and all statements of the scope of the invention which, as a matter of language, might be said to fall therebetween.

I claim:

1. In combination with the frame of a cot or bed, a spring supported by the frame, a 15 crank shaft having its ends pivoted at one end of the frame and its transverse portion extending from side to side of the frame so that the transverse portion is movable above and toward and from the bed spring, a head-rest frame pivotally supported upon the transverse portion of the crank shaft, a spring bar secured at one end to the bed frame and having a free end, and a stop lug carried by the free end of the spring bar 25 with which an edge portion of the head-rest frame engages to yieldably hold the head-rest frame in a desired adjusted relation whereby the headrest frame is adapted to yield with the yield of the bed spring.
2. In combination with the frame of a cot or bed, a spring supported by the frame, a 30 U-shaped crank shaft having bent ends

pivoted at one end of the frame and its transverse portion extending from side to side of the frame so that the transverse portion is movable above and toward and from the bed spring, a head-rest frame swingingly supported on the crank shaft and means secured to the bed frame engageable with one side of the swinging frame for yieldingly supporting said frame with respect to the bed spring. 35 40

3. In combination with the frame of a cot or bed, a spring supported by the frame, means pivotally supported on the frame, a 45 head-rest frame of less width than the width of the bed spring swingingly supported on the pivoted means and a spring bar secured to the bed frame having a free end and a stop on said end for yieldingly supporting 50 one side of the head-rest frame with respect to the bed spring.

4. In combination with the frame of a cot or bed, a spring supported by the frame, a crank shaft pivotally supported on the 55 frame and capable of being moved from a horizontal to a vertical position, a head-rest frame swingingly supported on the pivoted means and capable of being moved about the crank shaft, and means on the bed frame 60 for supporting the head-rest frame in adjustable position.

In testimony whereof I affix my signature.
MORRIS LIPPS.
